CLAIM

The ornamental design for a laryngoscope, as shown and described.

DESCRIPTION

FIG. 1 is a perspective view of an embodiment of the laryngoscope.

FIG. 2 is a bottom plan view of the laryngoscope.

FIG. 3 is a front elevational view of the laryngoscope.

FIG. 4 is a right side elevational view of the laryngoscope.

FIG. 5 is a left elevational view of the laryngoscope.

FIG. 6 is a rear elevational view of the laryngoscope; and,

FIG. 7 is a top plan view of the laryngoscope.

The broken lines shown in FIGS. 1–7 are included for the purpose of illustrating environmental elements only and form no part of the claimed design.

1 Claim, 3 Drawing Sheets
